UNITED STATES PATENT OFFICE.

ALBERT A. MACLEOD, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

WELT-BUTT-TACKING MACHINE.

1,007,711.

Specification of Letters Patent.

Patented Nov. 7, 1911.

Application filed March 11, 1911. Serial No. 613,893.

To all whom it may concern:

Be it known that I, ALBERT A. MACLEOD, a citizen of the United States, residing at Swampscott, in the county of Essex and 5 State of Massachusetts, have invented certain Improvements in Welt-Butt-Tacking Machines, of which the following description, in connection with the accompanying drawings, is a specification, like reference 10 characters on the drawings indicating like parts in the several figures.

This invention relates to machines for completing the shoe lasting operation by forcing over the last bottom and securing 15 the upper materials between the front heel seat tack and the end of the inseam at each side of the shoe. There is a space left by the sewing machine between the heel seat tacks and the beginning and the ending of 20 the seam because the sewing machine is unable to sew close to the tacks without loosening the tacks. An earlier machine for doing the work designed to be performed by the machine of this invention is shown 25 and described in British specification No. 22,839/08.

The object of the present invention is to improve said prior machine in certain respects which the practical use of that machine has suggested.

One important feature of this invention consists in mounting the upper tightening device to stand normally in a shoe receiving position substantially below the tacker. 35 This arrangement facilitates the presentation of the shoe to said device and the proper engagement of the shoe with said device to secure the desired upper tightening effect. Inasmuch as said device is designed for insertion in the crease between the upper and the welt the present arrangement avoids the necessity heretofore experienced for care in introducing the welt into a narrow space between the device and the 40 nozzle.

In accordance with a further feature the device, which is pivotally connected to its support for movement from and toward shoe receiving position, is held down yieldingly by a spring the force of which must 45

be overcome in lifting the shoe and the device into operative relation to the tacker. The purpose of this is to insure a substantial downward pressure of the device upon the shoe bottom in order that it shall hold 55 the shoe stock hard down upon the last bottom at the time a tack is driven. It is found in practice that by the use of this arrangement an operator can press the shoe against the engaging device to tighten the upper 60 over the edge of the last and will then, by lifting the shoe to the tacker, press or lay the tightened upper firmly down upon the insole in position for it to be so secured that the upper will not be crowded outwardly again when the shoe is subjected to 65 the heavy pressure of the heel attaching machine.

Another feature of the invention consists in the association with the upper tightening 70 blade employed in the earlier construction of means for engaging the shoe on the side and forcing the upper and the heel stiffener firmly against the side face of the last while the upper is being tightened. As is well 75 known, the heel stiffener and the stiff upper materials tend to bulge away from the said face of the last when they are bent over the last bottom. The means above mentioned serves to force said materials hard against 80 the side of the last and hold them there while the upper is being fastened, thus giving to the side of this portion of the shoe a better conformation to the shape of the last and a trimmer appearance.

Still a further feature of this invention consists in connections between the upper tightening device and the machine by which said device can be moved into an inoperative, out-of-the-way, position to permit the 90 use of the tacking apparatus for other work as, for example, for tacking innersoles to lasts. The object of this provision is to enable a single machine to be used for performing a plurality of operations in the 95 making of a shoe which heretofore have required separate machines. In carrying out this feature of the invention the upper tightening device is arranged for normal movement about its pivotal support through 100

an angle which is limited by a latch that can be withdrawn to permit the upper tightening device to swing down away from the tacker into a position in which a clear space 5 exists around the tacker for such presentation of the shoe as is required in tacking on the insole or similar operations.

The several features of the invention will appear more fully from the following description of the machine and will then be 10 pointed out in the claims.

Figure 1 is a side elevation of the machine embodying this invention in the best form now known to me; Fig. 2 is a perspective view looking downwardly toward the upper tightening device and the shoe bottom; Fig. 3 is a detail view illustrating the connection between the upper tightening device and the machine by which said device 20 may be rendered inoperative at times.

The frame of the machine supports a driving shaft upon which is loosely mounted the pulley 2, which has on its front or right-hand surface, as observed in Fig. 1, a friction face for engagement with the adjacent face of the cam block 4 that is fixed upon the shaft and through which the shaft is driven. The pulley is actuated toward the cam block, to cause the shaft to be driven, 30 by a spring 6 which connects the upper end of the lever 8 with the frame. The lever is forked to embrace the driving shaft and is fulcrumed at its lower end at 9 to the frame.

The lever 8 is provided at 10 with a steel 35 plate presenting a shoulder for engagement with a similar shoulder on a plate carried by the horizontal lever 12, which is fulcrumed to a swinging bar 14. This bar, which is pivoted to the frame at 15, has a 40 roll that engages with a groove in the cam block 4. The horizontal lever 12 extends forwardly over an abutment 16, shown as mounted for a slight pivotal movement, which is carried by the stem 18 of the vertically 45 movable nozzle 20 of the tacker.

The driving shaft is operatively connected through any suitable devices with means to deliver tacks to the inclined raceway 21, by which they are led to the nozzle 20. The 50 driver carried by the bar 22 is lifted by the cam 23 and actuated downwardly by the spring 24.

Between the machine frame and the post which carries it is an intermediate plate 25 55 having a forked forwardly extending end in which a carrier 30 is supported by a pivot pin 26. The carrier is in the form of an angle lever having a depending arm provided with an adjustable stop screw 28 to 60 limit the movement of the carrier about the pivot. The forwardly extending arm of the carrier supports a bar 32 upon the front end of which is mounted by an upright pivot the upper tightening device 35, said device having a thin blade-shaped end to enter the

crease between the welt and the upper and, it may be, for engagement with the end of the inseam. Said tightening device also comprises a downward extension shaped to engage the edge of the shoe and the side 70 face of the shoe below the edge for pressing the upper and the underlying heel stiffener firmly against the edge and side face of the last.

Upon the upper face of the bar 32 a plate 36 is held in endwise adjusted position by a binding screw 38. The front end face of this plate is arranged to engage the outer edge and face of the welt whereby the welt is positioned accurately with reference to the side face of the shoe. A plate 40 is pivotally connected to the plate 36 and adjustably held by a screw 42 spaced above said plate 36 to overlie and engage the upper face of the welt to prevent the welt from buckling 85 when it is pressed inwardly. A spring encircles the stem of the screw which connects the plates 36 and 40 holds the plate 40 in its uplifted position. The spring 45 is attached to the intermediate plate 25 and presses 90 downwardly upon the carrier 30 in front of its pivot 26 and requires a substantial force to be applied to the upper tightening device 35 for lifting said device and the shoe into position shown in dotted lines in Fig. 1 in 95 which the driver nozzle 20 is lifted for tripping the tacker wiper. A latch 46 is firmly supported by a pivot in the intermediate plate 25 and has an arm curved around the pivot pin 26 and extending under the lower 100 side face of the carrier 30, said latch providing sufficient vertical play to permit the normal movements of the carrier about its pivot indicated by the full and dotted lines in Fig. 1. The latch is held in its operative 105 position by a spring 47 but can be turned to withdraw it from the carrier 30 and permit the carrier then to swing down into a vertical position where unobstructed space around the nozzle 20 will be provided for 110 manipulating the shoe in tacking on insoles or other tacking operations. The latch 46 has a tail piece 48 which is the member with which the stop screw 28 contacts. When the latch is pressed backwardly this tail piece is 115 withdrawn from above the stop screw. The stop screw provides for varying the shoe receiving position of the upper tightening device.

The use of the machine and the purpose of 120 the improvements comprised in this invention having been sufficiently explained in the foregoing, I claim as new and desire to secure by Letters Patent of the United States:

1. In a machine for working into lasted 125 position the upper of a welt shoe adjacent to the ends of the inseam and the row of heel seat tacks, means constructed and arranged to engage the shoe stock between the upper and the welt end and tightening the 130

- upper about the last, means for engaging the side of the shoe at and immediately below the edge of the shoe bottom to force the upper and heel stiffener against the side of the last in said upper tightening operation, and means for securing the upper.
2. In a machine for working into lasted position the upper of a welt shoe adjacent to the ends of the inseam and the row of heel seat tacks, means constructed and arranged to engage the shoe stock comprising a blade to enter between the upper and the welt end, and a downward extension located with relation to the end of said blade to engage the side face of the shoe and press the upper and heel stiffener against the side of the last, and mechanism for securing the upper while it is held by said means.
3. In a machine for working into lasted position the upper of a welt shoe adjacent to the ends of the inseam and the row of heel seat tacks, a blade shaped to enter the welt crease and tighten the upper and having on its lower side a shoulder to engage the side of the shoe and press the upper and stiffener against the side face of the last and hold the stock in tightened condition while it is being secured.
4. In a machine for working into lasted position the upper of a welt shoe adjacent to the ends of the inseam and the row of heel seat tacks, a tacking apparatus, a support therefor, an intermediate plate arranged between said support and apparatus, a carrier pivotally connected to said intermediate plate, an upper tightening device mounted on said carrier and movable therewith from a shoe receiving position below the tacking apparatus upwardly into position for a tack to be driven to secure the stock in tightened position.
5. In a machine for working into lasted position the upper of a welt shoe adjacent to the ends of the inseam and the row of heel seat tacks, an upper tightening device, a support upon which said device is pivotally connected for movement upwardly from a shoe receiving position, tacking means toward which the shoe is so moved, and a spring, the tension of which must be overcome by pressing the shoe against the tightening device in a direction to force the shoe stock firmly down against the shoe bottom to prepare it for the reception of the securing tack.
6. In a machine for working into lasted position the upper of a welt shoe adjacent to the ends of the inseam and the row of heel seat tacks, a tacker, an upper tightening device arranged with relation to the tacker to engage a shoe in the welt crease and hold the shoe stock while the tack is driven and sustaining means for the tightening device arranged to permit said device to be moved away from the tacker and presented unobstructed space around the tacker for the purpose described.
7. In a machine for working into lasted position the upper of a welt shoe adjacent to the ends of the inseam and the row of heel seat tacks, a tacker, an upper tightening device arranged to hold the shoe stock in position to be secured by the tacker, a latch for maintaining the tightening device in position for use and adapted for manipulation to release the tightening device to allow the latter to be moved to a position remote from the tacker.
8. In a machine for working into lasted position the upper of a welt shoe adjacent to the ends of the inseam and the row of heel seat tacks, a tacker, an upper tightening device, a pivotal support for the latter, a latch permitting limited movement of the tightening device from shoe receiving position to shoe tacking position, said latch being arranged for movement to permit displacement of the tightening device to a position remote from the tacker for the purpose described.
9. In a machine for working into lasted position the upper of a welt shoe adjacent to the ends of the inseam and the row of heel seat tacks, a tacker, an upper tightening device, a support 25 to which said device is pivotally connected, a stop 28 for adjustably limiting the pivotal movement of said device, a latch 46 coöperating with said device and said stop to maintain the device normally in position for use, said latch being mounted for movement relatively to the device and the stop to permit the device to swing downwardly into position permitting use of the tacker alone.
10. In a machine for working into lasted position the upper of a welt shoe adjacent to the ends of the inseam and the row of heel seat tacks, a tacker, an upper tightening device arranged with relation to the tacker to receive a shoe in a position remote from the tacker and to move with the shoe and guide the latter into position for the upper tightened by it to be fastened by the tacker.
11. In a machine for working into lasted position the upper of a welt shoe adjacent to the ends of the inseam and the row of heel seat tacks, a tacker, a blade adapted to enter the welt crease and tighten the upper over the last, a support upon which said blade is pivotally mounted for movement from a shoe receiving position at a substantial distance below the tacker into position to hold the upper tightened while the tacker fastens it, and means for determining the shoe receiving position of the blade.
12. In a machine for working into lasted position the upper of a welt shoe adjacent to the ends of the inseam and the row of heel seat tacks, a tacker to insert a fastening

in the shoe bottom near its edge, and means including provision for positioning the shoe laterally relatively to the tacker and movable with the shoe from a shoe receiving position remote from the tacker into position to rest the shoe laterally for the tacking operation.

In testimony whereof I have signed my name to this specification in the presence of two subscribing witnesses.

Correction in Letters Patent No. 1,007,711.

It is hereby certified that in Letters Patent No. 1,007,711, granted November 7, 1911, upon the application of Albert A. MacLeod, of Swampscott, Massachusetts, for an improvement in "Welt-Butt-Tacking Machines," an error appears in the printed specification requiring correction as follows: Page 2, line 53, for the word "from" read *frame*; and that the said Letters Patent should be read with this correction therein that the same may conform to the record of the case in the Patent Office.

Signed and sealed this 5th day of December, A. D., 1911.

[SEAL.]

C. C. BILLINGS,

Acting Commissioner of Patents.

in the shoe bottom near its edge, and means including provision for positioning the shoe laterally relatively to the tacker and movable with the shoe from a shoe receiving position remote from the tacker into position to rest the shoe laterally for the tacking operation.

In testimony whereof I have signed my name to this specification in the presence of two subscribing witnesses.
